US00D819691S

(12) **United States Design Patent** (10) **Patent No.:** **US D819,691 S**
(45) **Date of Patent:** **** Jun. 5, 2018**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Matt Evans**, San Francisco, CA (US);
Sascha Höhne, Hamburg (DE);
Henrique Penha, San Francisco, CA (US)

(73) Assignee: **Apple Inc.**, Cupertino, CA (US)

(**) Term: **15 Years**

(21) Appl. No.: **29/582,884**

(22) Filed: **Oct. 31, 2016**

Related U.S. Application Data

(63) Continuation of application No. 29/548,474, filed on Dec. 14, 2015, now Pat. No. Des. 770,477, which is a continuation of application No. 29/470,457, filed on Oct. 22, 2013, now Pat. No. Des. 745,558.

(57)

CLAIM

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
